UNITED STATES PATENT OFFICE.

ALLAN COATS, OF NEWARK, NEW JERSEY, AND WILLIAM CAMERON, OF PAISLEY, SCOTLAND.

INTERNAL-COMBUSTION ENGINE.

1,364,482.

Specification of Letters Patent.

Patented Jan. 4, 1921.

Original application filed July 18, 1910, Serial No. 572,491. Divided and this application filed July 10, 1914. Serial No. 850,094.

To all whom it may concern:

Be it known that we, ALLAN COATS, a subject of the King of Great Britain, residing at Newark, in the county of Essex and State of New Jersey, U. S. A., and WILLIAM CAMERON, a subject of the King of Great Britain, residing at Paisley, Scotland, have invented certain Improvements in Internal-Combustion Engines, of which the following is a specification.

This invention relates especially to means controlling the inlet and exhaust of internal combustion engines and more particularly such engines of the four-cycle type, the present application being a division of our prior application Serial No. 572,491 filed July 18, 1910.

The objects of the invention are to provide a control comprising a sleeve in which there are two motions of different kinds, one longitudinally reciprocatory and the other rotary; to obtain by a combined reciprocating and oscillating motion a movement of the sleeve-valve port in the same direction along its path across the cylinder port; to thus secure such a movement of the sleeve-valve port without turning the sleeve-valve through successive complete rotations; to utilize the reciprocatory motion to control the opening of the exhaust and closing of the suction or inlet, and the rotary motion to control the closing of the exhaust and the opening of the suction; to provide suitable means for producing the said two motions; to secure by such two motions an efficient lubrication of the surfaces in contact, and to obtain other advantages and results as may be brought out in the following description.

Referring to the accompanying drawings, in which like numerals of reference indicate the same parts throughout the several figures,

Figure 1 is a central section of a vertical engine having a sleeve-valve and suitable operating mechanism for giving said sleeve-valve both a reciprocating and an oscillating motion;

Fig. 2 is a diagrammatic illustration of the sleeve valves of two cylinders of an engine such as shown in Fig. 8 and operating mechanism therefor;

Fig. 3 is a cross-section of the same, show-

ing the engine cylinders and taken through the inlet and exhaust ports of said cylinders;

Figs. 4 and 5 are diagrammatic elevations of the sleeve-valve with the sleeve-valve casing in section, Fig. 4 showing the movements of the port at the opening of the exhaust and Fig. 5 at the closing of the exhaust, and

Figs. 6 and 7 show diagrammatically the same sleeve-valve with its casing, itself and the cylinder in central longitudinal section, Fig. 6 illustrating the movement of the port at the opening of suction or inlet and Fig. 7 at the closing of the same.

In said drawings, and referring particularly to Fig. 1, 701 indicates the piston of an internal combustion engine working in cylinder 702. Said cylinder is surrounded by a water jacket 703 and has a head 704 in which the spark-plug 705 is mounted as is common. The spiral wheel 46 which is driven from the engine crank shaft 707 in any suitable manner gears into the wheel 47 whose revolutions are one-half that of the engine crank shaft. Wheel 47 is provided with a crank pin 48 which is free to move in the direction of its axis, and has an eye formed on its end through which passes a pin 49 secured to the sleeve-valve 706. The pin 49 is free to partly rotate about the axis of the hole in the crank pin 48, and thus as the outer sleeve-valve is oscillated the same pin 49 can turn slightly in said hole or eye of the crank pin 48 as it follows its curved path. The crank pin 48 can also slide in and out to accommodate this same curvature.

The movement which is given to the sleeve valve 706 by the crank pin 49 causes the exhaust port 712 and the inlet port 713 to register at the proper times with the exhaust and inlet ports 710 and 711 in the cylinder for the purpose of exhausting and admitting the working fluid from and to the cylinder. During the compression and firing strokes or periods the exhaust and inlet ports 712, 713 are placed above the ports 710 and 711 and on to the spring ring 719. We do not bind ourselves to the details of the drive shown, as for instance the pin 48 may be integral with the spiral wheel 47 and slide in a suitable hole in pin 49, the

wheel 47 may rotate on a central pin instead of as shown, or any other means may be used to give the sleeve valve 706 the described motion.

- 5 Figs. 2 and 3 illustrate diagrammatically a side elevation of two units of an engine which may consist of any number of such units, each unit being of the construction shown in detail in Fig. 1. The units are 10 noted by the Roman numerals I and II, and only one exhaust and suction port is shown in the sleeve-valves and cylinder in Fig. 2, for clearness.

Referring to unit I, Figs. 2 and 3, this 15 unit has just completed its compression stroke or period and is entering on the firing period of its cycle. The exhaust port 712 and the inlet port 713, are both above the exhaust and inlet ports 710, 711 of the cylinder, and on the spring ring (not shown) the rotary part of the movement which the sleeve valve 706 has is rapidly bringing the exhaust port 712 into line with the exhaust port 710 in the cylinder, and at the same 20 time, the said movement is rapidly taking the inlet port 713 farther out of alignment with the inlet port 711 in the cylinder. As the firing stroke proceeds and toward the end of that period the reciprocating component 25 of the combined movements given to the sleeve-valve predominates and both exhaust and inlet ports are rapidly taken off the spring ring, but only the exhaust port 712 is in alignment with its cylinder port 710. Therefore at the end of the firing 30 period, the exhaust port 712 begins to register with the exhaust port 710 in the cylinder, thus opening the exhaust port by the reciprocating component of the combined 35 movement.

Referring to unit II, Figs. 2 and 3, this 40 unit has completed its firing stroke or period and is on the exhaust period of its cycle. The reciprocating movement still predominates and the sleeve-valve 806 has now about 45 its maximum downward velocity and as the exhaust period of the engine cycle proceeds, the exhaust port 812 passes downward into full register with exhaust port 810 in the cylinder. The rotary component of the combined movement now predominates, its direction is changed and toward the end of the exhaust period the movement is purely 50 rotary. At about this time the exhaust period of the unit's cycle is closed by the edge of the exhaust port 812 in the sleeve valve passing out of register with the port 810 in the cylinder, it being remembered that the sleeve-valve is moving from right to left 55 when looking at exhaust port 812. Shortly after the closing of the exhaust port 810 in the cylinder, the edge of the inlet port 813 passes the edge of the inlet port 811 in the cylinder and the inlet ports 813 and 811 in 60 the sleeve-valve and cylinder begin to reg-

ister, the ports 813 and 812 being still in the same horizontal plane as ports 810 and 811. The exhaust period is thus closed and the inlet or suction period opened by the rotary movement of the sleeve-valve 816.

70

Figs. 4 to 7 inclusive, illustrate diagrammatically one cycle of the valve or port movements with reference to one unit such as shown in Figs. 1, 2 and 3, the position of the ports in the sleeve-valve in relation to 75 those in the cylinder being indicated for the opening and closing of the exhaust period of the unit's cycle and for the opening and closing of the inlet or suction period of the unit's cycle. The position of 80 the ports in the sleeve-valve during the compression and firing periods is indicated in Fig. 2 on unit I. Figs. 4 and 5 are part sectional elevations of a cylinder for a unit such as shown by Figs. 1, 2 and 3, the section 85 being through the sleeve valve casing in order to show the exhaust-port 712 in the sleeve-valve. Figs. 6 and 7 are sectional elevations of the said cylinder, the section being through the center line of the sleeve 90 valve-casing, sleeve-valve and cylinder in order to show the inlet ports more clearly. Only one inlet and exhaust port is indicated to avoid confusion, but the number and location of the ports in sleeve valve and cylinder 95 are as indicated in Fig. 3.

Referring to Fig. 4, the unit has completed its firing period and is about to commence its exhaust period, its crank pin 756 is moving in the direction of the arrow. 100 The sleeve crank pin 48 is moving in the direction of the arrow and the path of a point on the inner surface of the sleeve-valve is shown by the ellipse. When the unit's crank-pin 756 and the sleeve-valve 105 crank-pin 48 occupy the positions indicated, the movement of the sleeve-valve is practically in a vertical direction as the reciprocating component of the combined motion predominates, and at this instant its downward velocity is a maximum. The exhaust-port 712 in the sleeve is rapidly moving off the spring ring 719 and coming into register with the exhaust 710 in the cylinder, thus 110 opening the exhaust port 710 in the cylinder by the reciprocating movement of the sleeve-valve. As the exhaust period of the unit's cycle proceeds the reciprocating component of the combined movement disappears and at about the end of this period the movement of the sleeve-valve is practically purely 115 rotary. The sleeve-valve's crank-pin 48 having reached the position shown in Fig. 5, the unit's crank pin 56 is also in the position indicated in the Fig. 5. The sleeve-valve is now moving in the direction of the arrow with about its greatest velocity, rapidly closing the exhaust port 710 in the cylinder by the edge of the exhaust port 712 in 120 the sleeve-valve passing the edge of the ex- 125

130

haust port 710. On the crank pins 756 and 48 moving farther around in the indicated direction, the exhaust port is completely closed and the inlet port 713 begins to register with the inlet port 711 in the cylinder. This is shown in Fig. 6. From the position of the sleeve-valve crank pin 48 it is obvious that the rotary component of the combined movement still greatly predominates and that the movement of the sleeve-valve is still practically purely rotary. As the inlet port 713 is situated about diametrically opposite the exhaust port 712, see Fig. 3, it moves as shown by the dotted arrow in Fig. 6. Thus the closing of the exhaust period and opening of the inlet or suction period of the unit's cycle is brought about by the rotary movement of the sleeve-valve. As the suction or inlet period of the unit's 20 cycle proceeds, the rotary component of the combined movement disappears and when the crank pins 756 and 48 reach the positions indicated in Fig. 7, the movement of the sleeve-valve 706, as will be obvious from 25 the position of its crank-pin, 48, is practically in a vertically upward direction, the motion at this instant being purely a portion of a reciprocating movement. The sleeve-valve has now about its greatest upward velocity and the inlet port 713 is rapidly taken out of register with the inlet port 711 in the cylinder and placed on the spring ring 719, thus closing the suction period of the engine cycle by the reciprocating movement of the sleeve-valve. On the closure of 35 the inlet port 710, the unit enters on the compression period of its cycle and as this period progresses the reciprocating component of the combined movement disappears, and at about the end of the said period the motion of the sleeve-valve is practically purely rotary and in the opposite direction from that shown in Figs. 5 and 6, being now in the direction of 40 the arrow shown in Fig. 2, unit I. On this Fig. 2 is shown the position of ports 713, 712 which are as before mentioned on the spring ring 719 and the unit is just entering on the firing period of its cycle at the 45 end of which the sleeve-valve 706, its ports 712 and 713, and crank pin 48 again occupy the positions shown in Fig. 4.

We are aware that various other modifications of construction could be made without departing from the spirit and scope of our invention, and we do not wish to be understood as limiting ourselves to any particular means of obtaining the cycle of valve or port movements herein-described except as 55 the state of the art may require.

We have shown the sleeve-valve upon the outside of the cylinder and there are certain advantages in this, such as ease of access, better cooling, etc. At the same time 60 we wish it understood that the sleeve-valve

could be located upon the inside of the cylinder, and still our new cycle of valve or port movements secured with success.

Furthermore, we would have it understood that although we have in every case shown the spring ring to be above the exhaust and inlet ports in the cylinder, we may place the spring ring below these ports, in which case the downward part of the reciprocating movement given to the sleeve 75 valve would determine the closure of the inlet or suction period of the engine cycle, and the upward part of the said movement determine the opening of the exhaust period of the engine cycle. The crank or eccentric 80 operating the said sleeve-valve would turn in the opposite direction to that shown by the arrows, while the position of the crank or eccentric operating the sleeve-valve would, with reference to the engine crank 85 pin at the beginning of a period in the engine cycle, be altered.

In every instance, when the sleeve-valve is performing that portion of its cycle which effects the closure of the exhaust period and 90 opening of the suction or inlet period of the engine cycle, the rotary movement of the sleeve-valve is in one direction.

It will be noted that because of the two motions of different kinds which are imparted to the sleeve-valve distribution of lubricant upon the two contacting surfaces is greatly facilitated, and so a more perfect lubricating secured than by a purely reciprocating or purely rotary motion.

Having thus described the invention, what we claim is:

1. In an internal combustion engine, the combination with a cylinder having inlet and exhaust ports, a piston, and a crank shaft, of a sleeve in axial coincidence with said cylinder and having ports adapted to register with said ports of the cylinder, a rotary member at one side of said sleeve having its axis substantially perpendicular to the axis of the sleeve in a plane substantially perpendicular to the crank shaft, a crank pin pivotally connecting said rotary member and sleeve and slidable with respect to one of said parts, and means for rotating 105 said rotary member from the crank shaft.

2. In an internal combustion engine, the combination with a cylinder having inlet and exhaust ports, a piston, and a crank shaft, of a sleeve in axial coincidence with 110 said cylinder and having ports adapted to register with said ports of the cylinder, a gear wheel at one side of said sleeve having its axis substantially perpendicular to the axis of the sleeve in a plane substantially perpendicular to the crank shaft, a crank pin slidably mounted in said gear wheel, means pivotally connecting said crank pin to the sleeve, and means for driving said gear wheel from the crank shaft.

3. In an internal combustion engine, the combination with a cylinder having inlet and exhaust ports, a piston, a crank shaft, and a valve shaft substantially parallel to said crank shaft, of a sleeve in axial coincidence with said cylinder and having ports adapted to register with said ports of the cylinder, a rotary member at one side of the sleeve having its axis in a plane substantially perpendicular to the said valve shaft, means for driving said rotary member from said valve shaft, and a crank pin pivotally connecting said rotary member and sleeve and being slidable with respect to one of said parts.
4. In an internal combustion engine, the combination with a cylinder having inlet and exhaust ports, a piston, a crank shaft, and a valve shaft substantially parallel to said crank-shaft, of a sleeve in axial coincidence with said cylinder and having ports adapted to register with said ports of the cylinder, a worm wheel having its axis in a plane substantially perpendicular to the said valve shaft, a crank pin pivotally connecting said worm wheel and pin and having a sliding engagement with one of said ports, and a worm situated on said valve shaft engaging said worm wheel.
5. In an internal combustion engine, the combination with a cylinder, a piston, and a crank shaft, of a sleeve valve for said cylinder, a valve shaft at one side of a plane through the axes of said cylinder and crank shaft and substantially parallel to the crank shaft, and means transverse to said valve shaft connected at one end to the valve shaft and at the other end to the sleeve valve for imparting to said sleeve valve a combined reciprocatory and oscillatory movement.
6. In an internal combustion engine, the combination with a cylinder, a piston, and
- a crank shaft, of a sleeve valve for said cylinder, a valve shaft parallel to the crank shaft, and means transverse to the valve shaft connected at one end to said valve shaft and at the other end to the sleeve valve for imparting to said sleeve valve a combined reciprocatory and oscillatory movement.
7. In an internal combustion engine, the combination with a cylinder, a piston, and a crank shaft, of a sleeve valve for said cylinder, a valve shaft at one side of a plane through the axes of said cylinder and crank shaft and substantially parallel to the crank shaft, and means transverse to said valve shaft for imparting to said sleeve valve a combined reciprocatory and oscillatory movement, said means including a member connected at one end to the valve shaft and at the other end to the sleeve valve and held by one of said connections always parallel to a given line.
8. In an internal combustion engine, the combination with a cylinder, a piston, and a crank shaft, of a sleeve valve for said cylinder, a valve shaft parallel to the crank shaft, and means for imparting from said valve shaft to the sleeve valve a combined reciprocatory and oscillatory movement, said means including a member transverse to the valve shaft connected at one end to said valve shaft and at the other end to the sleeve valve and held by one of said connections always parallel to a given line.
